COMBINED TILTING STOOL AND BASKET

Talma T. Greenwood, Winchester, Mass.

Application March 30, 1935, Serial No. 13,946

8 Claims. (Cl. 155—134)

This invention relates to stools and particularly to a stool so constructed as to serve also as a tray or basket.

One of the objects of the present invention is the provision of a stool adapted primarily for use in the garden, the stool being so arranged that it has a broad areaed bottom part so that the stool does not sink into or undesirably mark the surface of the ground on which it rests, the stool being also capable of pivotal and rocking movement so that the user can bend forward and swing around to reach various parts of the garden, the stool being also so arranged that it will stand upright when not in use, and being further so arranged that it can be used as a basket to receive small garden tools, flowers, weeds, and the like, which can be placed in and taken from the stool when the stool is in service.

A yet further object of the invention is a stool comprising a seat, a bottom part and legs or uprights spacing and connecting the seat and bottom, the bottom part being concave on the bottom side and convex on the top side, the concave bottom part presenting a broad surface that supports the stool and the occupant thereof without embedding into the ground and permits the stool to be rocked and pivoted in any direction to permit the occupant to reach various parts of the garden, the bottom part being further characterized by having a flat middle portion of sufficiently broad area to support the stool stably in upright position when not in use and the concave upper face of the bottom functioning as a basket to receive various objects, the legs or uprights being sufficiently widely spaced apart the periphery of the bottom part as to allow unimpeded access to the basket.

A yet further object of the invention is the provision of a stool as above described wherein the seat portion has a handle so that the stool can be transported bodily like a basket, the handle being collapsible so that it can be placed out of the way when the seat is occupied.

Another object of the invention is the provision of a stool as above described wherein the bottom part has a downturned rim that engages the ground when the stool is tilted sufficiently and thereby acts as a stop to prevent further tilting of the stool to an unsafe degree.

A yet further object is generally to improve the construction of stools.

Fig. 1 is a perspective view of a stool embodying the present invention.

Fig. 2 is a plan view of the stool of Fig. 1.

Fig. 3 is a sectional elevation taken along line 3—3 of Fig. 2.

Fig. 4 is a sectional view taken along line 4—4 of Fig. 3.

Fig. 5 is an elevation of the stool in its extreme 5 tilted position.

Fig. 6 is an enlarged sectional detail showing the manner of securing the uprights or legs of the stool to the top and bottom members.

Fig. 7 is a view similar to Fig. 3 showing a modified construction.

The stool embodying the present invention comprises a circular top plate 10 constituting a seat, a circular bottom plate 12 of about the same diameter as the seat plate constituting the bottom support, and four legs or uprights 14 that space and connect the top and bottom plates. The legs are equiangularly spaced around the circumference of both plates. The seat plate 10 is formed of sheet metal of suitable thickness, is circular in configuration, and has a downturned peripheral flange 16 that not only increases the stiffness of the seat but at the same time presents a broad edge to the seat. The bottom plate 12 is also of sheet metal and is dish-shaped and has a circular 25 flat surface 18 in the middle thereof that is sufficiently broad so that it supports the stool in stable upright position when the stool is not in use. The bottom plate 12 beyond the middle flat portion 18 is convex on the bottom, as at 20, and is 30 correspondingly concave on its upper or inner face so that the edge 22 upstands above the bottom of the plate and forms a shallow tray or basket. The annular edge or rim portion 22 is 35 downturned so as to form a positive stop member, as is illustrated in Fig. 5, to limit the tilting of the stool beyond a safe position. The rim portion 22 also provides the bottom plate with increased resistance to deformation. The stool is 40 preferably not greatly higher than it is broad in diameter and the radius of the curvature of the concave portion 20 is preferably relatively large as, for instance, approximately three-quarters the height of the stool, so that the angle between the concave portion and the flat portion 18 is nearly 45 180°, and thus in the tilting of the stool the travel of the line of contact with the ground from the flat portion to the concave portion is unnoticeable, and also that the ground will not be marked in any harmful manner by the use and tilting of 50 the stool.

The legs or uprights 14 are of metal and preferably of channel or other structural shape in cross-section, as illustrated in Fig. 4. The upper ends 24 of the legs are reflexed inwardly toward 55

the center of the seat within the flange 16 and engage the bottom face of the seat and are suitably secured thereto as by spot welding. The lower ends 28 of the legs are also inwardly reflexed at an angle corresponding to the curvature of the concave portion 20 of the bottom and are also suitably secured thereto as by spot welding. Preferably the webs 30 of the channels extend into the reflexed end portions of the legs. The legs are secured to the peripheral portions of both the seat and the bottom plates so as to leave the concave inner face of the bottom plate free and clear to receive garden tools, flowers, and other objects. There is ample space between the legs to permit unimpeded access to the basket.

The stool is provided with a collapsible handle. For this purpose the seat is provided with a pair of openings or slots 32, the slots being located on opposite sides of the center of the seat. The handle comprises a thin metal strip having a handle portion 34 and at the ends thereof vertical legs 36 that are loosely disposed in the slots 32 and terminate in the out-turned feet 38 that underlie the bottom face of the seat and prevent the handle from being disengaged therefrom. Normally the handle portion rests loosely upon the top face of the seat but can be easily raised into the dotted line position of Fig. 5 and grasped by the hand to permit the seat and the loaded basket to be carried about.

In the modification illustrated in Fig. 7 the change in construction resides mainly in the manner of attaching the legs or uprights 14a to the seat and the bottom plates. In this modification the legs 14a are of channel shape as before but instead of having reflexed ends are terminated in square ends. The upper ends abut against the lower face of the seat plate and the lower ends abut against the downturned rim 22a of the bottom plate, the top face of which rim is for this purpose flat as at 40. In this modification the legs are preferably butt welded to both the seat and bottom plates.

The stool as thus constructed is light so that it can be carried readily by a woman into the various parts of the garden even when the basket contains the usual small garden tools, such as clippers, trowel, or the like, or when the basket is stacked with flowers or weeds.

Because of the broad area of the bottom plate the stool can be used upon the turf and upon the soft soil of a garden without sinking into or bedding down the soil in any deleterious manner. The pivoting and tilting functions of the stool are advantageous in permitting the user to lean forwardly or backwardly and swing around to reach a relatively large area of garden without shifting the position of the stool which has to be frequently done with a stool that can not tilt and pivot. The broad flat middle area of the stool permits the stool to stand stably in upright position when it is not in use so that the contents of the basket will not spill out. The basket is freely accessible even when the stool is in use and implements may be removed from and replaced in the basket and flowers and weeds may be placed therein while the occupant is seated upon the stool.

While the stool is described for use in connection with gardens it is by no means restricted to such use as it is useful as a general utility stool around the home and by mechanics, the rocking and pivotal movement of the stool facilitating

their work and the basket of the stool holding and transporting their tools.

I claim:

1. A tilting stool comprising a seat member and a circular dish-shaped bottom member of sheet material having a spheroidal convex ground-engaging bottom face, the middle part of said convex face having a circular flat part of sufficiently broad area to support the stool stably in upright position, and legs connecting and spacing said seat and bottom members and disposed about the peripheral portions thereof. 5

2. A tilting stool and basket comprising a seat plate and a circular spheroidal sheet metal bottom plate of dish-shape and convex on one side 15 and concave on the other side, the concave side confronting the seat plate and constituting a basket, and the convex side constituting a stool supporting surface on which the stool can tilt and pivot, the middle part of said bottom plate 20 having a flat circular part of sufficiently broad area to support the stool stably in upright position, and legs connected to and rising from the peripheral part of said bottom plate and attached to the seat plate, the legs being peripherally 25 spaced to permit unimpeded access to the interior of the basket.

3. A tilting stool comprising a seat member and a circular dish-shaped bottom member of sheet material having a spheroidal convex ground-engaging bottom face, the middle part of said convex face having a circular flat part of sufficiently broad area to support the stool stably in upright position, and legs connecting and spacing said seat and bottom members, said bottom member 30 having a peripheral downturned flange constituting both an annular stop limiting the tilting of the stool and a reinforcing rim for said bottom member.

4. A tilting stool and basket comprising a seat plate and a circular spheroidal dish-shaped bottom plate of sheet material convex on one side and concave on the other side, the concave side confronting the seat plate and constituting a basket, and the convex side constituting a stool supporting surface on which the stool can tilt and pivot, the middle part of said bottom plate having a flat circular part of sufficiently broad area to support the stool stably in upright position, and legs connected to and rising from the peripheral part of said bottom plate and attached to the seat plate, the legs being peripherally spaced to permit unimpeded access to the interior of the basket, said bottom member having a peripheral downturned flange constituting both an annular 45 stop limiting the tilting of the stool and a reinforcing rim for said bottom member. 50

5. A tilting stool comprising a seat member and a circular dish-shaped bottom member of sheet material having a spheroidal convex ground-engaging bottom face, the middle part of said convex face having a circular flat part of sufficiently broad area to support the stool stably in upright position, and legs connecting and spacing said seat and bottom members, the upper face of 60 said bottom member having an upstanding peripheral part and thereby constituting a basket, and said legs rising from and spaced about said peripheral part. 65

6. A tilting stool comprising a seat member and a circular dish-shaped bottom member of sheet material having a spheroidal convex ground-engaging bottom face, the middle part of said convex face having a circular flat part of sufficiently broad area to support the stool stably in 70 75

upright position, and legs connecting and spacing said seat and bottom members, and a handle connected with the middle part of said seat and having means by which it is movable into service and out of use positions.

7. A tilting stool and basket comprising a seat plate and a circular spheroidal dish-shaped bottom plate of sheet material convex on one side and concave on the other side, the concave side confronting the seat plate and constituting a basket, the convex side constituting a stool supporting surface on which the stool can tilt and pivot, the middle part of said bottom plate having a flat circular part of sufficiently broad area to support the stool stably in upright position, legs connected to and rising from the peripheral part of said bottom plate and attached to the seat plate, the legs being peripherally spaced to permit unimpeded access to the interior of the basket, and a handle connected with the middle part of said seat and having means by which it is movable into service and out of use positions.

8. A combined tilting stool and basket comprising a seat plate and a circular spheroidal dish-shaped bottom plate of sheet material concave on one side and convex on the other side, both plates having approximately the same diameter, the concave side of said bottom plate facing said seat plate and constituting a basket, the convex side constituting a stool supporting surface on which the stool can pivot and tilt in any direction, the middle part of said bottom plate having a flat circular part of sufficiently broad area as to support the stool stably in upright position, said bottom plate having a down-turned annular flange that is terminated below the top edge of said bottom plate but above said flat part and constitutes a stop that limits the tilting of the stool, legs attached to the peripheral concave side of said bottom plate and to said seat plate, said legs being peripherally spaced to provide free access to said basket, and a collapsible handle carried by the middle part of said seat plate.
